ARTICLE OF LUGGAGE

Albert W. Winship, Utica, N. Y., assignor to Winship Company, Inc., Utica, N. Y., a corporation of New York

Application February 15, 1956, Serial No. 40,180

Term of patent 14 years

(Cl. D87—5)

FIG. 1

I claim:

The ornamental design for an article of luggage, substantially as shown.
